UNITED STATES PATENT OFFICE.

EDWIN W. M. BAILEY, OF AMESBURY, MASSACHUSETTS.

WINDOW-GLASS CHANNEL.

Application filed July 7, 1927. Serial No. 203,943.

This invention relates to that type of metal window glass channels which are primarily designed for use in closed automobile bodies to receive the edges of the window glass employed therein, and more particularly to means for installing the same.

It is usually desirable to install these channels after the construction of the body has been practically finished, and while the installation in casing grooves thereof about the window openings has not involved serious difficulty, such installation in the enclosed space into which the window is lowered has been found to be particularly difficult, as means for securing the channel in position like that used about the opening cannot be employed.

The object of my invention is to provide a form of metal channel or guide for the edge of the window glass, which may be readily inserted in the position in which it is to be held from the top of the enclosed space below the window opening, and which will be securely held in the position in which it is inserted.

I accomplish this object by means of the construction hereinafter described, and as illustrated in the accompanying drawing in which:

Fig. 1 is a front elevation of a window glass channel embodying my invention and shown in position in a casing.

Fig. 2 is a sectional view at line 2—2 of Fig. 1.

Fig. 3 is a sectional view at line 3—3 of Fig. 1.

Fig. 4 is a side elevation of the lower end portion of a window glass channel embodying my invention.

In the drawing, *a*, indicates a casing located directly beneath a window opening and adapted to receive the window glass when lowered therein, and *b* indicates the top rails between which the glass slides. A sheet metal window glass channel *e* of the type shown in my prior Patent No. 1,571,831 is provided, said channel having a bottom, or base and two sides and being preferably felt lined and adapted for use in connection with a similar guide in the casing of the window opening in the manner indicated in my Patent No. 1,635,570.

According to my invention a series of tongues *d* are cut from each side of the channel at suitable intervals, each tongue being

formed by a longitudinal slit intermediate the side and two transverse slits extending from the ends of the longitudinal slit to the base, and being bent outward from the side into approximately the plane of the base. Whether the tongues are opposite each other, or alternately placed is not important, so far as their functions are concerned, and the number employed may be varied according to conditions.

In the construction of the body a guideway *e*, which merely consists of a flat strip of metal, having its edge portions bent inward to form oppositely disposed grooves *f*, is secured to the inner side of the casing on which the channel is to be located, and extends from top to bottom thereof, said groove being adapted and arranged to receive the end portions of the tongue *d*, when inserted therein, so that, to install the channel, it is merely necessary to slide the same downward in the guideway, the tongues *d* extending into said grooves, as shown in Fig. 2.

As the metal from which the tongues are formed is thin, it is difficult to form the grooves in the guideway so that the tongues will fit closely therein. To obviate this difficulty the tongues are bent obliquely at one end portion thereof, so that the effective thickness thereof is increased to correspond to the width of the grooves and a portion of each tongue will bear on each side of the groove in which it is located.

As the material of which the channel is formed is somewhat resilient, a firm engagement of the tongues with the guides will be secured at all times and the danger of rattling in the future will be avoided.

To provide a stop for supporting the channel in position, one or more prongs *g* may be struck out from the metal of the guide *e*, which will engage the base portion of the channel, as shown in Figs. 1 and 3, and, for the purpose increasing the rigidity with which the channel is held, the sides of the channel are preferably cut from their edges to the base and laid flat with the base and then bent double to form a reenforced end portion *h* having projecting tongues *d'*.

With the above described construction, the channel may be readily inserted after the door, or other construction has been finished, and, when in position will be rigidly held so that all possibility of rattling will be avoided. The form of guide shown is not expensive.

and less expensive forms may be employed. The tongues may be formed from the channel by a simple mechanical operation.

I claim:

5. 1. In combination with a casing, a sheet metal window glass channel composed of a base and two sides and having one or more tongues cut from each side and bent outward in position to project laterally therefrom adjacent the base and a guideway secured to the casing having oppositely disposed grooves arranged to receive said tongues.
10. 2. In combination with a casing, a sheet metal window glass channel composed of a base and two sides and having one or more tongues cut from each side and bent outward at the base to project oppositely approximately in the plane thereof and a guideway secured to the casing and having oppositely disposed grooves arranged to receive said tongues.
15. 3. In combination with a window casing, having oppositely disposed grooves, a window glass channel of somewhat resilient sheet metal and composed of a base and two sides, said channel having one or more tongues cut from each side and bent outward therefrom to project into said grooves from adjacent the base, said tongues having their end portions bent obliquely with relation to the sides of the grooves for resilient engagement.
20. 4. In combination with a window casing, having oppositely disposed parallel grooves, a resilient metal window glass channel having tongues formed therewith and projecting beyond its sides adjacent its base and slidably engaged in said grooves, the distance

between the adjacent sides of the grooves being substantially greater than the thickness of the metal from which the tongues are formed and said tongues each having a portion bent obliquely to another portion thereof thereby to provide opposite faces for resilient engagement with the sides of the groove.

40. 5. In combination with a window casing having a pair of guideways disposed in parallelism and opening towards each other at opposite sides of the plane in which the window glass is to be held and a sheet metal channel for receiving the edge portion of the window glass arranged with its base portion between said guideways and having one or more tongues cut therefrom and bent outward at each side adjacent the base in position to engage the sides of the guideways which face towards the casing and hold the channel in position thereon.

45. 6. In combination with a window casing having a pair of guideways disposed in parallelism and opening towards each other at opposite sides of the plane in which the window glass is to be held and a sheet metal channel for receiving the edge portion of the window glass arranged with its base portion 50 between said guideways and having one or more tongues cut from each side thereof and bent outward adjacent the base in position to engage the sides of the guideways which face towards the casing and hold the channel in position thereon.

55. In testimony whereof, I have signed my name to this specification.

EDWIN W. M. BAILEY.
